COMBINED SOLDERING IRON HOLDER AND TRANSFORMER UNIT

Alden J. Brassaw, Phillipsburg, N.J., assignor to Weller
Electric Corporation, Easton, Pa., a corporation of
Pennsylvania

Filed July 19, 1965, Ser. No. 86,212

Term of patent 14 years

(Cl. D26—1)

Fig. 1

Fig. 2

FIG-3

FIG-4

FIG-5

FIGURE 1 is a front, top and right side perspective view of a combined soldering iron holder and transformer unit, showing my new design;

FIGURE 2 is a left side elevational view, the right side being substantially a mirror image thereof;

FIGURE 3 is a top plan view;

FIGURE 4 is a front elevational view; and,

FIGURE 5 is a rear elevational view thereof.

I claim:

The ornamental design for a combined soldering iron holder and transformer unit, substantially as shown and described.
